UNITED STATES PATENT OFFICE.

MARTIN G. HOFFMAN, OF MERRILL, AND JOHN H. HIEB, OF GRAND RAPIDS, WISCONSIN.

AUTOMATIC FIRE-KINDLER.

SPECIFICATION forming part of Letters Patent No. 728,107, dated May 12, 1903.

Application filed October 17, 1902. Serial No. 127,695. (No model.)

To all whom it may concern:

Be it known that we, MARTIN G. HOFFMAN, residing at the city of Merrill, in the county of Lincoln, and JOHN H. HIEB, residing at the city of Grand Rapids, in the county of Wood, State of Wisconsin, citizens of the United States, (and whose joint post-office address is Merrill, Lincoln county, Wisconsin,) have invented new and useful Improvements in Fire-kindlers, of which the following is a specification.

Our invention relates to fire-kindlers; and the object is to provide a fire-kindler of improved kind which is associated with a time mechanism, whereby at a determined time ignition may be automatically accomplished and the effects may be communicated to the kindling material as desired and required.

The invention embodies the combination, with the alarm mechanism of a clock, of a fulminated and inflammable element ignited at a determined moment by the alarm mechanism, as will be hereinafter fully specified and the novelty thereof particularly pointed out and distinctly claimed.

We have fully and clearly illustrated one form of the invention in the accompanying drawings, to be taken as a part of this specification, and wherein—

Figure 1 is a rear elevation of a timepiece equipped with our improved fire-kindling mechanism and fuse. Fig. 2 is a sectional view of a portion of clock mechanism, showing a spring-arm which bears the friction-plate on the fuse. Fig. 3 is a vertical section of a portion of a clock mechanism, showing the friction plate or shoe, the friction-wheel, and the spring. Fig. 4 is a detail perspective view of the spring-actuated friction plate or shoe.

It will be premised that the invention is designed for attachment to the alarm mechanism of a clock and produces ignition of a fulminate arranged to communicate its effects to inflammable substances in a fire-pot of a stove, range, or furnace. In the present instance a friction disk or pulley mounted on the arbor or shaft of the alarm-wheel and a spring-actuated shoe are utilized to effect the purpose.

Referring to the drawings, A designates a

clock casing or shell of a well-known type, made of sheet metal, and therefore well adapted for the purpose of having the attachments associated therewith. 1 designates the winding-arbor of the alarm, 2 the shaft which carries the tappet-wheel, and 3 the tappet. 4 is the winding-shaft. These parts or elements of the clock, together with the whole clock mechanism, are well known and need not be particularly described.

The shaft 2 is extended to reach a proper distance out from the back of the clock-case and has fixedly mounted on the projecting end a rotatory friction disk or pulley 5, the periphery of which may either be smooth or milled or roughened, so the proper friction may be produced when rotated in contact with a relatively stationary member.

To the back plate of the clock is pivotally secured an arm or plate extending vertically and formed with a flange or shoe 6, the inner surface of which bears against the circumferential face of the rotatory friction-wheel 5, as shown in the drawings. The arm or plate is extended above the shoe 6 and formed into a flat disk portion 7, having a laterally-extending finger-piece 8 to afford convenient manipulation. The disk affords protection to the back of the clock during the burning of the fulminate, and at a suitable point the arm is provided with an ear or lug 9.

On the setting-arbor 11 of the clock is mounted a spring 10, having one limb or arm lodged against the winding-arbor 4 of the clock and the other arm extended vertically and formed with a lateral extension 10^a, which projects through a curved slot 10^b in the back plate of the clock and engages in the lug 9 and holds the shoe 6, bearing in the direction of the rotary disk or wheel 5, as indicated in the drawings. At the lower end the shoe 6 is formed with a rearward extension 11^a, having an open-end slot 12, wherein the end of the fuse is disposed and held from slipping.

13 designates a strand of inflammable material supplied with an easily-ignited portion or fulminate at the part posited between the friction-disk and the shoe of the spring-pressed arm, and for the rest of the length the strand is saturated with a free-burning

ingredient, so that when the fulminate is ignited the strand will be set on fire and the flame travel the length thereof to the point where the flames are utilized to ignite the material in the fire-pot.

To utilize the invention, the alarm is set to the time desired, and then the inflammable strand is disposed with its end in the slot 12 and the fulminated portion arranged between the shoe and the friction-disk, with the strand having proper connection in the fire-box of the stove or other device in which a fire is to be enkindled. The clock may then be placed in a desired position on the stove, and the enkindling will take place at the time determined upon. It will be observed that when the disk 5 is rotated and the fulminated strand is between the shoe and the disk the fulminate will be ignited and the flame will travel over the strand or fuse and eventually reach the fire-pot.

Having thus fully described the invention, what is claimed as new is—

1. The combination with the alarm mechanism of a clock having the arbor of its alarm-wheel extended through the back plate, and a friction-disk on the extended end of the arbor, of a pivotally-supported arm formed with a shoe to bear against the friction-disk and a protecting-disk at its upper portion,

and a spring mounted within the clock and formed with a lateral extension projecting through the back plate of the clock and engaging the pivotally-supported arm to the shoe and the rotary friction-disk.

35

2. The combination with the alarm mechanism of a clock having the arbor of its alarm-wheel extended through the back plate, and a friction-disk on the projecting end of the arbor, of a pivotally-supported arm formed with a shoe, a slotted extension at the lower end of the shoe, and a broadened upper protecting portion, and a spring mounted within the clock and formed with a lateral extension projecting through the back plate of the clock and engaging the pivotally-supported arm to move it toward the friction-disk.
